(57) **CLAIM**

The ornamental design for the solar light, as shown and described.

DESCRIPTION

FIG. 1 is a three-dimensional view of a solar light showing my new design;

FIG. 2 is a front view thereof;

FIG. 3 is a top view thereof, and,

FIG. 4 is a bottom view thereof.

The broken lines shown on the drawings are for illustrative purposes only and form no part of the claimed design.
